UNITED STATES PATENT OFFICE.

ERNEST F. FISHER, OF ST. LOUIS, MISSOURI.

VAPOR GENERATOR AND SUPERHEATER.

Application filed September 4, 1924. Serial No. 735,862.

My invention has relation to improvements in vapor generators and superheaters and consists in the novel features of construction more fully set forth in the specification and pointed out in the claims.

The principal object of the invention is to generate steam and cause the same to be superheated by increasing the pressure thereof within a suitable mixing chamber wherein the steam is mixed with hot gases. Applicant is aware that heretofore steam generators have been devised wherein the steam was mixed with hot gases, but the degree to which the steam could be heated was limited in these devices owing to the fact that no provision was made for increasing the pressure thereof above that of atmospheric pressure. Applicant's improvement contemplates the provision of a fan or other device whereby the steam after being generated is mixed with a large volume of hot gases in a confined chamber where their pressure is greatly increased.

The manner of accomplishing this object together with the other advantages possessed by this invention will be better apparent by a more detailed description of the same in connection with the accompanying drawings, in which—

Figure 1 is a vertical longitudinal section taken on the line 1—1 of Fig. 2 (with parts in elevation) of my improved generator and superheater; Fig. 2 is a plan view of the invention; and Fig. 3 is a horizontal cross section on the line 3—3 of Fig. 1.

Referring to the drawings, B represents a suitable base extending upwardly from which is a hollow pedestal 7 on the upper end of which is fixed a housing 2 provided with a downwardly extending annular flange 2' which receives the pedestal 7. Positioned within the pedestal 7 at about the middle thereof is a gas burner 6 above which there is a water container or a boiler 4. Within the boiler 4 and disposed along the axis thereof is a flue or open ended pipe 5, said flue being provided with a series of annularly disposed openings 10 immediately below the bottom wall of the housing 2. The space between the boiler 4 and the top of the pedestal 7 is closed by a wall *w* so that the only outlet for the steam and vapor arising within the boiler 4 is through the openings 10 into the flue 5 whence such products discharge into a mixing chamber C within the housing 2. A motor 1 is mounted on the top

of the housing 2, the drive shaft 1' of which projects through the top wall of said housing and carries on its extremity a fan or exhauster 3, the intake opening O of which receives the upper end of the flue 5. The side walls 15 of the housing 2 are each provided with an outlet opening 16, two of which communicate with hollow ironing tables 8 and 9 and one of which (in the present instance) has connected to it a flexible hose 11 terminating in a brush 12.

It is understood that from the opening 16 the steam may be led to any desired point of application for such purpose as one may see fit, such as heating or even cooking.

The operation of my invention briefly may be described as follows:

We will assume that the water container 4 is provided with the desired amount of water and that the gas is turned into the burner 6 and ignited. Thereafter, the steam and vapor will rise within the container 4 and the products of combustion and hot gases will rise within the flue 5, said steam and heated products of combustion commingling within the upper part of the flue 5 and then discharging into the casing C which serves as a mixing chamber. Now, if the fan 3

is not in operation the steam will move slowly under the influence of atmospheric pressure into the hollow tables 8 and 9. But on putting the fan 3 into operation the steam and products of combustion will be rapidly exhausted by the action of the fan from the flue 5 and expelled into chamber C at the same time being rapidly and thoroughly mixed within said chamber. Since the outlet of the mixed steam and products of combustion from the chamber C is inadequate

to allow such products to discharge freely from such chamber the pressure of the steam within the chamber will be greatly increased and the steam will therein become superheated and discharged with greatly increased velocity through the opening 16 in the housing wall 15. The great advantage of superheated steam at high pressure within the casing C is that the steam may be conducted by means of a pipe connected to either of the outlets, 13 or 14 to some reasonably distant point which could not be done if the steam exhausted in the casing only under atmospheric pressure.

Having described my invention, I claim:

1. A steam generator and superheater

comprising a burner, a water container adjacent thereto, a flue for the products of combustion from the burner adjacent to the water container, a housing having a mixing chamber in communication with both the water container and the flue, and a fan for exhausting the products of combustion from the flue into said mixing chamber, said chamber having restricted outlets.

2. A steam generator and superheater comprising a burner, a water container adjacent thereto, a flue for the products of combustion from the burner within the water container, a housing having a mixing chamber, a fan within said mixing chamber, said fan having an intake in communication with the water container and flue and an outlet communicating with the mixing chamber, and said mixing chamber having restricted outlets.

3. A steam generator and superheater comprising a water container, means for heating the water therein, means associated

with said water container for superheating the steam generated therein, a housing having a chamber in communication with the water container, said chamber being provided with restricted outlets, and means for increasing the pressure of the vapor in said chamber above atmospheric pressure.

4. A steam generator and superheater comprising a water container, means for heating the water therein, means associated with said water container for superheating the steam generated therein, a housing having a chamber in communication with the water container, said chamber having a restricted outlet, means for increasing the pressure of the vapor in said chamber above atmospheric pressure, and means associated with said superheating means for introducing heated atmospheric air in the said chamber.

In testimony wherof I hereunto affix my signature.

ERNEST F. FISHER.
